UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed October 5, 1921. Serial No. 505,603.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to sound-deadening 10 devices for typewriting machines, and comprises a casing which encloses the sound-producing parts of the machine, while permitting the ordinary typing operations to be carried on. For this purpose, the casing 15 comprises a body-part and a cover-part, the body-part enclosing all of the typewriting machine with the exception of the forward extension in which are positioned the banks of typewriter keys.

20 The cover extends from the front to the rear of the body-part to completely close the latter at the top. The front edge of the cover-part forms with the body-part a slot through which the various carriage-operating levers may extend to be operable 25 from outside the casing. Ordinarily, to provide access to the mechanism at the top of the machine, as for the purpose of inserting or adjusting work-sheets around the 30 platen, it would be necessary to swing the cover-part out of the way until the forward edge thereof was clear of the top of the body-part. This would necessitate swinging the cover-part through a comparatively 35 great distance. It is a feature of this invention to provide a cover-part which need be swung through only a comparatively small distance to allow access to the top of the machine. This feature is particularly 40 desirable where the typewriting machine is provided with a collating table which projects upwardly and necessitates considerable clearance space to the rear thereof in order to permit access to the paper-table at the 45 rear of the carriage for insertion of work-sheets. For this purpose, the cover-part is constructed in two parts, one of which swings forwardly and the other rearwardly, so that each part uncovers half of the body-part at the top. In this manner the inconvenience of moving a single-piece cover too far to the rear is avoided, and, by the above construction, the parts of the cover are more readily accessible at all times. Said parts 50 also counterbalance each other, thus elimi-

nating the use of counterbalance springs usually employed with a one-piece cover.

A further feature of this invention is a connection between the parts of the cover whereby swinging of one part to open or 60 closed position by the operator will cause the other part to swing simultaneously to corresponding open or closed position.

Suitable means is provided to determine 65 the open positions of the cover sections.

Other features and advantages will hereinafter appear.

In the accompanying drawings,

Figure 1 is a side view, vertically sectioned, of a sound-deadening casing applied 70 to an Underwood Standard typewriting machine, said machine being provided with a collating table, and a part of the machine being broken away.

Figure 2 is a view similar to Figure 1, 75 but with the cover-part in open position.

Figure 3 is a horizontal section of the device shown in Figure 1, the section being taken on the line 3—3 of Figure 1.

Figure 4 is a perspective view of the casing applied to the machine.

The Underwood Standard typewriting machine comprises a main frame 10, supported upon a base by feet 11 and having a forward extension 12 of said main frame 85 in which are positioned banks of keys 13, operating type-bars 14 to cause types 15 carried thereby to strike against a platen 16. Said platen is mounted in a platen-frame 17, forming part of a carriage 20 mounted for letter-feeding movement upon a front rail 21 and a rear rail 22 on the main frame. Said carriage is provided with various forwardly-extending finger-pieces including the line-space handle 25. 90 For certain types of work it may be desirable to provide a collating table 26 at the front of the platen, upon which work-sheets may be adjusted relatively to each other and relatively to the printing point. One form of collating table is shown in the patent to C. B. Corell, No. 1,262,310, dated April 9, 1918.

For deadening the sounds arising in the typing operation, there is provided a sound-deadening casing comprising a body-part 30 and a top or cover-part indicated generally at 32. Said body-part has a rear wall 33, side walls 34, lateral extensions 35 on said side walls over which said carriage operates 105 110

to the right and left, and a removable front wall 36, said front wall, when removed, providing an opening through which the machine may be inserted into the casing. The 5 machine may be positioned relatively to the casing by holes 40 in a plate 40^a extending from side to side at the bottom of the casing, said holes receiving the rear feet of the machine.

10 For enclosing the machine at the top, there is provided the cover-part 32 consisting of a forward section 41 pivoted at 41^a and a rearward section 42, the latter being hinged at 43 to the rear wall of the body- 15 part. If the cover-part 32 consisted of one piece swingable about the hinge 43, considerable more weight, due to increased height of the cover caused by the height of the collating table, would have to be lifted by the 20 typist. Further, it would be necessary to swing the cover rearwardly until the free edges thereof were considerably behind the collating table, so as to permit a work-sheet to be freely inserted behind the platen and 25 said collating table. If the collating table were of a height greater than that of the one shown herein, it would obstruct the cover and keep it from being opened. To avoid the above-mentioned difficulties, the cover- 30 part is constructed in the two sections 41 and 42 both pivotally mounted on the body-part and having their meeting edges substantially equidistant from the front and rear edges of the body-part. By swinging 35 one part forwardly and the other part rearwardly, the entire top of the machine may be uncovered, the rearward part moving but a fraction of the distance ordinarily required by the single-piece cover. The forward section 41 is preferably in the form of 40 a frame having a front wall 49 and depending side walls 50 overlapping the sides of the body-part and pivoted thereon, said front wall being provided with a window 51 to permit the machine in the interior of the 45 casing to be viewed. The rear section 42 has a ceiling 55 to form a continuation of front wall 49 when the parts are in closed position, and side walls 56 to form continuations of the side walls 50. To prevent escape of sound through the meeting edges of the side walls of the forward and rearward parts of the cover, the side walls of one part, here shown as the forward section, are provided with overlapping portions 57. When 50 the cover-part is in closed position, the side walls 50 and 56 form sound-proof sides for the cover-part and are continuations of the sides of the extensions 35 which they over- 55 lap to form an effective closure at the sides between the cover-part and the body-part. The forward edge 45 of section 41 terminates some distance above the top of front wall or plate 36 when the cover is in closed 60 position to form a slot through which the

forwardly-extending carriage finger-pieces, such as line-space lever 25, extend. To close the slot, there are provided co-operating sound-deadening cushions 60 and 61 mounted on part 41 and on front plate 36, respectively. 70

It is desirable to provide means whereby swinging of the forward section 41 forwardly will simultaneously swing the rear section 42 rearwardly. For this purpose, 75 any suitable connection may be provided, there being herein shown a link 65 connected at one end to one side wall 50 of the section 41, and at the other end to an ear 66 on the corresponding side wall 56 of the section 42. The link is attached to side wall 50 in such manner that swinging the section 41 forwardly will draw said link forwardly and upwardly, and hence draw ear 66 forwardly and upwardly to swing section 42 80 forwardly and upwardly to rearwardly. This linkage may be duplicated at the other side of the casing to provide an easier lifting action. The weight of the forward and rearward parts tends to hold these parts in closed position until the forward part is drawn forwardly. It will be seen that the link 65 and the side wall 50 with which it is connected form substantially a toggle between the pivot 41^a and the pivot at the rear end of link 65, and that when the toggle is straight the rear section 90 will be locked in closed position. For convenience in swinging the forward part it may be provided with a finger-piece 70. 95

To limit the open positions of the cover sections, there may be provided a stop 75 to be engaged by the ear or arm 66 of the rear section 42. As shown in Figure 2, the front section 41 is overbalanced to so great an extent as to render certain the holding 100 of the rear section 42 in open position. 105

It will be understood that by constructing the cover with two pivoted sections, connected to each other to swing simultaneously to open and closed positions, it may be more readily manipulated, since the sections have a tendency to counterbalance each other, thus avoiding the necessity of separate devices, such as springs, which are usually employed to assist in swinging the cover to open position when the cover is made of one piece. 110 115

The casing may be lined with any suitable kind of sound-deadening material.

Variations may be resorted to within the scope of the invention, and portions of the improvements may be used without others.

Having thus described my invention, I claim:

1. A combined sound-deadening casing and typewriting machine having a carriage, said casing including a body-part, and said carriage having paper-controlling means including an auxiliary device rising from said carriage substantially above said body-part, 125 130

a top for said body-part comprising a section in rear of said auxiliary paper device and hinged to the body-part and having a rear wall and side walls, and a section in front of said auxiliary device and having a forwardly and downwardly inclined window and side walls pivoted on the body-part, and connections between the front section and rear section to cause them to move 10 simultaneously to open or closed positions.

2. A combined sound-deadening casing and typewriting machine having a carriage, said casing including a body-part, and said carriage having paper-controlling means including an auxiliary device rising from said carriage substantially above said body-part, a top for said body-part comprising a section in rear of said auxiliary paper device and hinged to the body-part and having a 20 rear wall and side walls, and a section in front of said auxiliary device and having a forwardly and downwardly inclined window and side walls pivoted on the body-part, and connections between the front section and rear section to cause them to move simultaneously to open or closed positions, said connections serving to lock the rear section in closed position when the front section is in closed position.

3. A combined sound-deadening casing and typewriting machine having a carriage, said casing including a body-part, and said carriage having paper-controlling means including an auxiliary device rising from said carriage substantially above said body-part, a top for said body-part comprising a section in rear of said auxiliary paper device and hinged to the body-part and having a rear wall and side walls, and a section in 40 front of said auxiliary device and having a forwardly and downwardly inclined window and side walls pivoted on the body-part, and a toggle connection between the front section and the rear section to cause simultaneous movement to open or closed positions and straight when the sections are closed to lock the rear section in closed position.

4. A sound-deadening casing for a typewriting machine having a traveling carriage, a platen therein and a collating table at the delivery side of the platen, said casing comprising a body-part having a rear wall and side walls, and said collating table 50 rising substantially above said body-part, and a cover for said body-part to receive said collating table and including a front section pivoted to said body-part, said cover closing over the upper end of said collating table and at the sides.

5. A sound-deadening casing for a typewriting machine having a traveling carriage, a platen therein and a collating table at the delivery side of the platen, said casing comprising a body-part having a rear wall and

side walls, and a cover for said body-part to receive said collating table, said cover comprising front and rear sections pivoted to said body-part at the front and rear, respectively, and meeting at the top over the 70 upper end of said collating table and overlapping at the sides along lines substantially parallel to said collating table.

6. A sound-deadening casing for a typewriting machine having a frame, a traveling carriage thereon, a platen in said carriage and an upwardly-projecting collating table at the delivery side of the platen, said casing comprising a body-part to receive the frame and having a rear wall and side walls, 75 and a cover having a rear section with a rear wall hinged at its lower edge to the rear wall of the body-part and extending upwardly and forwardly to a position above and adjacent the upper edge of said collating table, and side walls having their forward edges extending downwardly substantially parallel to the collating table, and a front section having a ceiling extending downwardly and forwardly to the front of 80 the body-part and side walls to engage the side walls of the rear section, and having downward extensions so pivoted to the side walls of the body-part that the front section may be swung, lower edge foremost, down 85 at the front of the body-part.

7. A sound-deadening casing for a typewriting machine having a frame, a traveling carriage thereon, a platen in said carriage and an upwardly-projecting collating table at the delivery side of the platen, said casing comprising a body-part to receive the frame and having a rear wall and side walls, a cover having a rear section with a rear wall hinged at its lower edge to the rear wall of 90 the body-part and extending upwardly and forwardly to a position above and adjacent the upper edge of said collating table, and a front section having a ceiling extending downwardly and forwardly to the front of 95 the body-part, and having downward extensions so pivoted that the front section may be swung, lower edge foremost, down at the front of the body-part, and a connection between the front and rear sections of the 100 cover to cause simultaneous swinging of the front and rear sections to and from their closed positions.

8. A sound-deadening casing for a typewriting machine having a frame, a traveling carriage thereon, a platen in said carriage and an upwardly-projecting collating table at the delivery side of the platen, said casing comprising a body-part to receive the frame and having a rear wall and side walls, 120 a cover having a rear section with a rear wall hinged at its lower edge to the rear wall of the body-part and extending upwardly and forwardly to a position above and adjacent the upper edge of said collat- 125

65 130

ing table, and side walls having their forward edges extending downwardly substantially parallel to the collating table, and a front section having a ceiling extending downwardly and forwardly to the front of the body-part and side walls to engage the side walls of the rear section, and having downward extensions so pivoted to the side walls of the body-part that the front section may be swung, lower edge foremost, down at the front of the body-part, and a connection between the side walls of the front and rear sections of the cover to cause simultaneous swinging of the front and rear sections to and from their closed positions, said connection comprising a link at one side of the casing pivoted at its forward end to the corresponding side wall of the front section of the cover, and at the other end to a downward extension of the corresponding side wall of the rear section.

9. A combined typewriting machine and sound-deadening casing therefor, said casing comprising a body and a top portion, said typewriting machine comprising a carriage having paper-controlling means including a part which rises substantially above the body of the casing, said top extending up from said body and closing over said rising part, and including a front window portion supported to swing bodily forwardly and downwardly off from said casing.

10. A combined typewriting machine and sound-deadening casing therefor, said casing comprising a body and a top portion, said typewriting machine comprising a carriage having paper-controlling means including a part which rises substantially above the body of the casing, said top extending up from said body and closing over said rising part, and including a front window portion supported to swing bodily forwardly and downwardly off from said casing, said top also comprising a rear portion which is supported to swing rearwardly; and connections between said top portions for causing them to move together in opposite directions into open and closed positions.

11. In a sound-deadening casing for a typewriting machine having a carriage and a finger-piece projecting forwardly therefrom, said casing comprising a body-part having a rear wall, side walls and a front closure-plate, a cover comprising a front section forming with said front closure-plate a slot through which said finger-piece projects, and pivoted on the body-part

to be swung, forward edge foremost, down at the front of the body-part, and a rear section hinged to the rear wall of the body-part, and a connection between said sections for opening and closing the rear section by opening and closing the front section.

12. A combined sound-deadening casing and typewriting machine having a traveling carriage, a platen therein and a collating table at the delivery side of the platen, said casing comprising a body-part having a rear wall and side walls, and said collating table rising far above said body-part, and a cover extending upward from both front and rear and comprising a front window section and a rear section, both sections hinged to the body-part and closing over said collating table.

13. A combined sound-deadening casing and typewriting machine having a traveling carriage, a platen therein and a collating table at the delivery side of the platen, said casing comprising a body-part having a rear wall and side walls, and said collating table rising far above said body-part, and a cover extending upward from both front and rear and comprising a front window section and a rear section, both sections hinged to the body-part and closing over said collating table, said front section hinged to swing forwardly off from the casing, and said rear section hinged to swing rearwardly.

14. A combined sound-deadening casing and typewriting machine having a frame, a traveling carriage thereon, a platen in said carriage and an upwardly-projecting paper-table on said carriage, said casing including a body-part to receive the frame and a rear top portion extending upwardly and forwardly adjacent said collating table, and a front top portion having a window extending downwardly and forwardly and having downward extensions so pivoted to the body-part that the front section may be swung down at the front of the body-part.

15. A sound-deadening casing for a typewriting machine, comprising a body and a two-part cover, the forward part supported to swing forwardly and downwardly and bodily below the top of the casing-body, and connections between the parts for constraining them to move together in opposite directions into open and closed positions, said connections including a toggle-joint, straight when the parts are closed.

JOHN WALDHEIM.
